UNITED STATES PATENT OFFICE.

CARL HILLE, OF ALTA, IOWA.

SAILBOAT.

Application filed October 12, 1927. Serial No. 225,696.

The object of my invention is to provide a sail boat of simple and novel construction, particularly designed for speed and for safety when travelling at high speed.

5 For accomplishing the above purpose, it is my further object to provide in connection with a sail boat, a pair of laterally spaced stabilizers in the form of members substantially lighter than water and adapted to 10 travel on or in the water depending upon the position of the boat.

Another object is to provide means for supporting said stabilizers from the hull of the sail boat including preferably pivoted 15 arms and to provide means for adjusting the stabilizers and said pivoted arms for varying the position of the stabilizers with relation to the boat.

Still a further purpose is to provide such 20 stabilizers with upper air compartments and with lower compartments adapted to hold water, which lower compartments are provided with valves controllable from the deck of the sail boat.

25 Another purpose of my present invention is to provide a bowsprit for the fore sail and means for securing the bowsprit either extended forwardly from the mast or laterally therefrom.

30 Still another purpose is to provide in such a sail boat, a novel braking or retarding means for slowing the speed of the boat quickly where such slowing down is necessary.

35 Although the invention is susceptible of a variety of embodiments, it is unnecessary to fully describe and illustrate more than one in order to give a full understanding of the invention both from its structural and functional standpoints.

With these and other objects in view my invention consists in the construction, arrangement and combination of the various parts of my device, whereby the objects contemplated are attained, as hereinafter more fully set forth, pointed out in my claims and illustrated in the accompanying drawings, in which:

Figure 1 shows a top or plan view of the 50 sail boat embodying my invention.

Figure 2 shows a side elevation of the same.

Figure 3 is a detail longitudinal sectional

view through one of the stabilizers and is taken on the line 3—3 of Figure 1.

55

Figure 4 is a vertical sectional view through the brake or retarding device.

Figure 5 is a detail sectional view taken on the line 5—5 of Figure 2.

Figure 6 is a detail sectional view taken on the line 6—6 of Figure 1.

Figure 7 is a sectional view taken on the line 7—7 of Figure 1 showing one of the stabilizers in rear elevation and part of the sail boat hull in section; and

65

Figure 8 is an enlarged sectional detail view of the lower part of one of the stabilizers, illustrating the construction of one of the controlling valves therein.

In the accompanying drawings, I have 70 used the reference numeral 10 to indicate the hull of my improved sail boat. The boat may if desired, be provided with a center board 12. It also has the usual rudder 14. The hull 10 and the stabilizers hereinafter 75 more fully described, are so constructed and proportioned that normally the body of the boat and the front ends of the stabilizers, rest high in the water as illustrated in Figure 2 where the water level is indicated 80 at 16.

The sail boat has the usual mast, main 85 sail 20, top sail 22, flying jib 24 and fore sail 26. The pulleys and tackle for the sail are illustrated more diagrammatically because they do not in themselves form a part of my present invention except as herein-after more fully set forth.

My sail boat is intended for fast sailing and the hull is therefore relatively narrow. 90 On each side of the sail boat I provide stabilizers which are indicated generally by the reference numerals 28.

Each stabilizer consists of a hollow body having generally the shape of a boat. The 95 body of each stabilizer 28 has an interior horizontal partition 30. Above the partition is an air tight compartment 32 for giving the stabilizer ample buoyancy.

On the top or deck of the stabilizers 28 are brackets 34 to which are journaled the pivot members 36. The members 36 are downturned from rods 40 which are pivoted to the hull 10 as at 42 and extend laterally as shown in Figure 1. For each stabilizer 100 there are two of the pivoted rods 40.

Cables 44 are secured to the forward ends of the stabilizers 28 and extend to the prow of the boat and are suitably adjustably anchored. By adjusting the cables 44, the 5 stabilizers 28 may be adjusted to different positions with relation to the hull 10. The rods 40 are arched upwardly as clearly illustrated in Figure 6 of the drawings to be well above the waves so that they do not impede 10 the progress of the sail boat. Suitable braces 56 and 58 are provided to lend rigidity to the rods 40.

In the bottom of each stabilizer 28 is a pair of hinged doors or valves 46. The 15 hinges 52 for the doors 46 are of the spring type so that the doors are normally closed by the springs. Tubes 48 extend through the partition 30 and deck 28 of each stabilizer.

20 Secured to each valve or door 46 is a controlling lever 50 which when moved to the dotted line position (Fig. 8) will open the door 46. Suitable gaskets 54 are provided for forming a water tight joint when the 25 doors are closed. A stop arm 96 is provided on the door 46 to limit the amount of its opening movement.

Cables 60 and 62 are secured to the outer 30 ends of the levers 50 and extend up through their respective tubes 48. The cables 60 and 62 extend from the tubes 48 toward the hull 10 and are secured to cable drums 64 which are controlled by hand wheels 66. From the foregoing description it will be obvious 35 that by adjusting the cables 60 and 62, the valves or doors 46 may be opened or closed as desired for admitting water to or allowing it to drain from the lower compartment 68 of the stabilizer. There is sufficient 40 clearance around the cables 60 and 62 within the tubes 48 to allow free flow of air into and out of the lower compartment of the stabilizer to take the place of water flowing outwardly through the doors 46 or to be displaced by water flowing inwardly through 45 the doors as the case may be. Thus in fast sailing, the stabilizers will be sufficiently buoyant when emptied of water to prevent too great careening of the sail boat.

50 It will be noted that I have provided two valves 46 in each stabilizer 28. The forward valve 46 opens downwardly and forwardly while the rear valve opens downwardly and rearwardly. By this arrangement 55 the valves 46 may be manipulated to assist in filling or emptying the compartment 68 of water. For instance when the forward valve is opened it will scoop water up into the stabilizer and when the rear 60 valve is opened the stabilizer will be quickly emptied of water even with the door dragging in the water over which the boat is sailing.

The stabilizers function in two ways. For 65 instance, if the sail boat is turning to the

right, the right hand stabilizer may be left empty of water and its buoyancy will thereby lessen the tilting of the hull 10. The skipper will know of his purpose to turn to the right and will at the proper time 70 have opened the forward valve 46 of the left hand stabilizer and allow that stabilizer to take water into the compartment 68. Then in making a right turn, the weight of the stabilizer will also contribute to causing 75 the hull 10 to maintain its equilibrium.

It will thus be observed, that the stabilizers may be adjusted to different positions and that their buoyancy and weight may be controlled by the skipper in such a manner 80 so as to give him a control of his sail boat which would otherwise be impossible.

By using these stabilizers, the weight of the boat may be greatly increased, the handling of the boat will be greatly facilitated 85 and safety in handling it will be substantially increased. This is of considerable importance in speed boats and those used for racing, because it stabilizes the sail boat in heavy breezes and facilitates the rapid 90 maneuvering of the boat.

For greatly increasing the speed of such sail boat, I provide the following means. The bowsprit 70 is pivoted to the mast 18 in the usual way and, of course, normally 95 projects forwardly beyond the bow of the boat. Near the bow of the boat it rests in a block 72 and is securely locked there by means of a pin 74 projected through suitable holes in the upstanding arms 72^a of the block 72 above the bowsprit.

I provide similar blocks 72 on the deck of the hull 10 on the left and on the right of the mast 18 so that by removing the pin 74, the bowsprit may be lifted from the forward block 72 and rested in either the right or left end block 72 as illustrated for example by dotted lines in Figure 1.

By swinging the fore sail in one direction of the boat and the main sail almost in the opposite direction of the boat, the boat can be sailed almost directly before the wind. This is made possible by the arrangement for securing the bowsprit, for instance, in the dotted line position shown in Figure 1 115 and by the stabilizers already described.

Such an arrangement greatly increases the possible speed of the boat. By the use of the stabilizers, it is possible for the boat to carry much more sail than would be otherwise possible.

I have provided another means for facilitating quick maneuvering of the boat and for slowing it down quickly. By referring to Figures 1, 2 and 4, it will be noted that there is provided rearwardly of the center board 125 12, a brake which is built much like the ordinary center board.

In the hull of the sail boat 10 I provide a well 76 of the usual kind provided for center 130

boards. Slidably mounted for vertical reciprocation in the well 76 is a brake member 78 built very much like an ordinary center board. On the front face of the upwardly projected board 78, I provide a toothed rack bar 80.

Suitably journaled in brackets 82 and 84 on the frame of the well 76, is a shaft 86 on which is a crank handle 87 (in Figure 1). 10 On the shaft 86 is a pinion 88 which meshes with the rack bar 80. One of the brackets 84 carries a pivoted pawl 90 coacting with the pinion 88.

In case it is desired to quickly slow the 15 boat down, the pawl 90 is thrown out of engagement with the pinion 88 and the crank handle 87 may be manipulated for rotating the shaft 86 and the pinion 88 for lowering the brake 78. The brake 78 when lowered 20 into the water, will quickly impede and reduce the speed of the boat.

The brake is used in approaching a dock or in making a sharp turn around a buoy or wherever the handling of a boat may make 25 the use of the brake advisable. It will thus be seen, that I have provided a sail boat which on account of the features of structure herein described, can carry more sail than is otherwise possible and therefore, have 30 greater speed.

I have provided means for providing ample safety in such a boat. I have also provided means as hereinbefore described, which makes the maneuvering of such a boat easy 35 and rapid.

It will be understood that changes may be made in the details of the construction and arrangement of the parts of my improved sail boat, without departing from the real 40 spirit and purpose of my invention.

Ordinarily the stabilizers 28 draw about six inches of water when the hull 10 is on an even keel. This arrangement could be changed according to the size of the boat 45 and according to the conditions under which it is to be used.

I have, for instance, shown suitable rubber gaskets 54 around the valves or doors 46. Any suitable gasket may be employed and 50 the forms of these valves might be greatly modified.

It is my purpose to cover by my claims any such modified forms of structure or any use of mechanical equivalents which may be 55 reasonably used within my claims.

I claim as my invention:

1. In combination with a boat, a pair of stabilizers spaced laterally on opposite sides of the boat, said stabilizers having upper 60 compartments and lower compartments, valves for admitting water to or permitting water to be discharged from the lower compartments, means for controlling said valves

from the boat and means for allowing the outflow or inflow of air relative to said lower 65 compartments.

2. In combination with a boat, a pair of stabilizers spaced laterally on opposite sides of the boat, said stabilizers having upper compartments and lower compartments, 70 valves for admitting water to or permitting water to be discharged from the lower compartments and means for controlling said valves from the boat, said means including cables projected through the upper compartments but not in communication therewith and means for adjusting said cables.

3. In a device of the class described, a sail boat, a pair of stabilizers arranged on opposite sides of the boat, spaced supporting 80 members pivoted to the boat and pivoted at their outer ends to the stabilizers, cables for connecting the front ends of the stabilizers with the boat forwardly of the stabilizers, each stabilizer having an upper buoyant 85 compartment and a lower buoyant compartment, a valve in the lower compartment comprising a hinged member, a lever thereon and a cable secured to said lever and extended 90 to the hull of the boat.

4. In a device of the class described, a sail boat, a pair of stabilizers arranged on opposite sides of the boat, spaced supporting members pivoted to the boat and pivoted at their outer ends to the stabilizers, cables for 95 connecting the front ends of the stabilizers with the boat forwardly of the stabilizers, each stabilizer having an upper buoyant compartment and a lower buoyant compartment, a valve in the lower compartment comprising a hinged member, a lever secured there- 100 to and a cable secured to said lever and ex- tended to the hull of the boat, and means including a hand wheel and cable drum for tightening the cable and thereby opening the 105 door.

5. In combination with a boat, a stabilizer secured thereto and spaced from the side thereof, an openable door in said stabilizer for admitting water thereto or allowing it 110 to be drained therefrom, a partition in said stabilizer to prevent it from completely filling with water and means of communication between the atmosphere and said stabilizer below said partition.

6. In combination with a boat, a stabilizer secured thereto and spaced from the side thereof, a pair of openable doors in said stabilizer, one of said doors opening forwardly and the other one rearwardly, means 115 for normally maintaining said door closed and means extending from said door to the boat and operable for opening the door.

Des Moines, Iowa, September 12, 1927.

CARL HILLE.
